(**) Term: **14 Years**

(57) **CLAIM**

(21) Appl. No.: **29/127,892**

The ornamental design for a recoil buffer, as shown and described.

(22) Filed: **Aug. 14, 2000**

DESCRIPTION

(51) LOC (7) Cl. **22-01**

FIG. 1 is an front prospective view of the recoil buffer.

(52) U.S. Cl. **D22/111; D22/108**

FIG. 2 is an rear prospective view of the recoil buffer.

(58) Field of Search D22/108, 111;

FIG. 3 is a front view of the recoil buffer.

89/14.3, 44.02, 198

FIG. 4 is a back view of the recoil buffer.

(56) **References Cited**

FIG. 5 is a top view of the recoil buffer.

U.S. PATENT DOCUMENTS

FIG. 6 is a bottom view of the recoil buffer.

D. 328,632 * 8/1992 Bigwood D22/108
D. 380,249 * 6/1997 Bingham et al. D22/108

FIG. 7 is a side view of the recoil buffer; and,

FIG. 8 is an opposite side view of the recoil buffer.
